US00D933685S

(12) **United States Design Patent** (10) Patent No.: **US D933,685 S**
 (45) Date of Patent: **** Oct. 19, 2021**

(54) **DISPLAY PANEL OR PORTION THEREOF WITH GRAPHICAL USER INTERFACE**

(71) Applicant: **MAGIC LEAP, INC.**, Plantation, FL (US)

(72) Inventors: **Lorena Pazmino**, Wilton Manors, FL (US); **Karen Stolzenberg**, Fort Lauderdale, FL (US); **Tim Zurmoehle**, Fort Lauderdale, FL (US); **Andrea Isabel Montoya**, Plantation, FL (US)

(73) Assignee: **Magic Leap, Inc.**, Plantation, FL (US)

(**) Term: **15 Years**

(21) Appl. No.: **29/734,523**

(22) Filed: **May 13, 2020**

Related U.S. Application Data

(62) Division of application No. 29/640,722, filed on Mar. 16, 2018, now Pat. No. Des. 899,435.

(51) **LOC (13) Cl.** **14-04**

(52) **U.S. Cl.** **D14/485**

CLAIM

The ornamental design for a display panel or portion thereof with a graphical user interface, as shown and described.

DESCRIPTION

The sole FIGURE is a front view of a display panel or portion thereof with a graphical user interface showing our design.

The outermost broken line rectangle illustrates a display panel or portion thereof and forms no part of the claimed design. The remaining broken lines, including all text, illustrate portions of the graphical user interface or a mixed reality environment, and form no part of the claimed design.

1 Claim, 1 Drawing Sheet
